UNITED STATES PATENT OFFICE.

OWEN ENOS NEWTON, OF FORT MADISON, IOWA.

SEAL-LOCK.

SPECIFICATION forming part of Letters Patent No. 307,320, dated October 28, 1884.

Application filed January 17, 1884. (No model.)

To all whom it may concern:

Be it known that I, OWEN ENOS NEWTON, a citizen of the United States, residing at Fort Madison, in the county of Lee and State of Iowa, have invented certain new and useful Improvements in Seal-Locks, of which the following is a description.

This invention relates to seal-locks for securing freight-car and other doors; and the invention consists of the novel construction hereinafter described and claimed.

In the drawings, Figure 1 is a side elevation of my seal-lock, partly in section, also showing a view of the key detached. Fig. 2 is a similar view showing the lock applied to an eyebolt or pin instead of a hasp or staple. Fig. 3 is a side elevation, partly broken away, showing my invention adapted to a spring-key. Fig. 4 is a similar view showing the lock provided with a projection whereby it may be driven from the bolt. Fig. 5 is a section on line *x x* of Fig. 4, showing a modification by which a leaden shot may be used as a key, and Fig. 6 is an elevation, partly in section, showing my invention in the form of a padlock.

A indicates the casing of the lock, which may be bolted in suitable position for receiving the pin *b*, or secured by a chain, *C*, as shown in Fig. 4. In the casing is formed a key-seat, *D*, having closed ends *E*, one or both of which ends may be made flaring outward, and transversely to the key-seat, and on each side of the hole *H* for pin *B* is a recess or groove, *F*, for receiving the ends of the key when the pin is being forced out, as shown in Fig. 1. The walls of the recesses *F* may be beveled off at *G* to facilitate the passage of the key in forcing the pin from the lock. The pin *B* has a slot or lateral recess, *I*, formed in it, which is adapted to register with the key-seat *D* to receive a wire key, *J*, which is to be inserted into the closed seat by means of a small aperture, *K*, leading obliquely thereto. The key consists, preferably, of a straight piece of wire, as shown in Figs. 1 and 2; but it may have a loop at one end for attaching a small tag, as shown in Fig. 4, or it may be made of a piece of wire bent double or **U**-shaped to form a spring, as shown in Fig. 3, which is to be compressed to insert it into the

seat. In inserting the latter the loop end, to which a tag may be attached, is to enter first, and when the ends have passed the aperture *K* they will spring apart into the flaring recess at the end of the seat, from which they cannot again be extracted through said aperture. When the pin *B* and the lock are forced apart, the wire key will be bent up or down into the recesses *F*, the beveled walls *G* in Figs. 3 and 4 serving to turn the ends of the key down and to guide them into the recesses as the pin *B* is driven out.

L indicates the door-hasp, and *M* the staple, through which the pin *B* is passed to confine the hasp.

L' is an eyebolt or pin, which takes the place of the hasp and staple on some cars, the pin or bolt being inserted through the door into the jamb, and being locked by the pin *B*, which passes through its eye into the lock.

M' is a staple for securing the lock in position.

As shown in Fig. 4, the lock may be made comparatively small and inexpensive, in which case it is formed with a shoulder, *N*, by which it may be driven off the end of the pin *B* with a hammer. In such case the lock is to be secured by a chain, *C*, to allow it the necessary movement in removing and replacing the same.

The key already described may be used on this form of the lock; but I do not wish to restrict myself to the use of the wire key. I have therefore shown in Fig. 5 a construction in which the lateral recess *I* in the pin *B* is beveled toward the end of the pin, and a small aperture, *P*, is formed through the front side of the casing opposite to said recess, so that a leaden shot, *O*, may be dropped therein. The shot will wedge between the wall of the pin-seat *H* and the beveled surface of the recess *I*, and finally be flattened between the pin and its seat in the separation of the pin and lock.

As shown in Fig. 6, the pin *B*, instead of being straight, may be made **U**-shaped, and the head may be confined and adapted to slide in a recess, *Q*, in the casing *A*, while the end of the pin is adapted to be secured in the lock in the manner above described.

Instead of inserting the pin *B* with its point downward, as shown in Figs. 3, 4, 5, and 6, it

may be reversed in position, and the lock arranged above the hasp or pin L', as shown in Figs. 1 and 2. This position will always indicate that the pin is locked, without the necessity of examination. It may be driven out by hammering on the point.

I do not limit myself to any special shape of the lock or means of securing it in place, since these may be varied without altering 10 the character of the lock.

What I claim is—

1. The combination of the pin having a recess or slot formed therein, the lock-casing having a concealed key-seat, with which the 15 slot or recess in the pin may be made to register, and a key adapted to be inserted into the said seat and endwise through the pin through an opening in the casing, substantially as shown and described.
2. The seal-lock having the key-seat D, closed at both ends, and the pin-hole H, the pin-hole being arranged transversely to the key-seat, and recesses or grooves F at the sides of the pin-hole, substantially as shown 25 and described.
3. The combination, with a lock-casing having a concealed key-seat, and a recessed pin inserted into the casing of the seal-lock key, consisting of the straight piece of wire 30 cut of a length corresponding to the length of the key-seat, substantially as shown and described.
4. The combination, with a pin having a slot or recess therein, of a movable cap-like 35 seal-lock having an internal key-seat, and a straight wire key adapted to enter said key-seat and engage with the pin, substantially as shown and described.

5. The combination, with a pin, of a seal-lock having an internal or concealed key 40 adapted to engage with the pin, and having a shoulder by which it may be forced from the pin by a hammer, substantially as shown and described.

6. The combination, with a pin having a 45 slot or recess therein, of a seal-lock having a key-seat formed with closed ends, and an aperture leading obliquely to said seat, and a key formed of a piece of wire, substantially as shown and described.

7. The combination, with a pin having a slot or recess therein, of a seal-lock having a key-seat formed with closed ends, and an aperture leading obliquely to said seat, and having recesses at the center on opposite sides 55 of the pin-seat, which are provided with beveled walls leading to the pin-seat, and a key formed of a piece of wire, substantially as shown and described.

8. The combination, with a U-shaped pin 60 having a slot or recess therein, of a seal-lock casing having a recess for confining the head of the pin, whereby the latter may move vertically therein, and having a key-seat formed with closed ends, and an aperture leading obliquely to said seat, and a key formed of flexible metal adapted to engage with the slot in 65 the end of the pin, substantially as shown and described.

OWEN ENOS NEWTON.
